US0D1101322S

(12) **United States Design Patent** (10) **Patent No.:** **US D1,101,322 S**
(45) **Date of Patent:** **** Nov. 4, 2025**

(54) **ROBOTIC CLEANER**

(71) Applicant: **Anker Innovations Technology Co., Ltd.**, Changsha (CN)

(72) Inventors: **Qisheng Peng**, Shenzhen (CN); **Sangmin Yu**, Shenzhen (CN); **Yuhang Lei**, Shenzhen (CN); **Jihui Lai**, Shenzhen (CN)

(73) Assignee: **Anker Innovations Technology Co., Ltd.**, Changsha (CN)

(**) Term: **15 Years**

(21) Appl. No.: **29/922,510**

(22) Filed: **Dec. 22, 2023**

(30) **Foreign Application Priority Data**

Jun. 30, 2023 (CN) 202330407253.0

(51) **LOC (15) Cl.** **15-05**

(52) **U.S. Cl.**

USPC **D32/23**

(58) **Field of Classification Search**

USPC D15/199; D21/526, 578; D32/15, 16, D32/19, 20, 21, 38

CLAIM

The ornamental design for a robotic cleaner as shown and described.

DESCRIPTION

FIG. 1 is a front top perspective view of a robotic cleaner showing our new design;

FIG. 2 is a bottom rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken lines shown in the drawings depict portions of the robotic cleaner that form no part of the claimed design.

1 Claim, 8 Drawing Sheets
